UNITED STATES PATENT OFFICE.

ROBERT HOWARD BIGGS, OF ST. CATHARINES, ONTARIO, CANADA.

GARTER.

Application filed June 29, 1925. Serial No. 40,405.

My invention relates to improvements in garters of the type comprising a non-elastic band divided intermediately of its length, and a metallic resilient connector detachably connecting the ends of the band together, and carrying means for attachment to the sock of the wearer, and the object of the invention is to simplify and cheapen the construction and thereby reduce the cost of manufacture, and it consists essentially of the arrangement and construction of parts as hereinafter more particularly explained.

Fig. 1 is a perspective view of my garter applied to the leg of a wearer.

Fig. 2 is a detail view of the cast off.

Fig. 3 is a detail of the knob plate connecting with the cast off.

Fig. 4 is a sectional view on line 4—4 Figure 2.

Fig. 5 is a sectional view on line 5—5 Figure 2.

In the drawings like characters of reference indicate corresponding parts in each figure.

1 indicates a band of non-elastic material which is passed around the leg of a wearer as indicated and formed at one end into a loop 2 connected to an adjusting bar 3 which is 20 slidable upon the band 1 in order to adjust the length of the band in proportion to the size of garter required according to common practice.

4 is a cast off comprising an elongated loop portion 5 which is passed through the loop 2 and is therefore held adjacent to the adjusting bar 3. Centrally of the length of the loop 5 the cast off is formed into a forward extending loop 6.

7 is a cross piece preferably provided with a central recess 8. The cross piece 7 is provided with orifices 9 and 10 through which the side arms of the forwardly extending loop 6 slidably extends.

11 is a fine coiled spring which is wound around the loop 6 at the outside of the cross piece 7 so as to bear at its free end against such cross piece.

12 is a pad which is secured to the opposite end of the band 1 and to which is secured a metal plate 13 by means of stitching 14 passing through the fabric of the pad 12 and through the slotted openings 15 of the plate. The plate 13 is provided with

a forward extension 16 from which extends 55 a knob or other headed member 17.

18 is a suspender member by which the lower end of the pad 12 is connected to the stocking of the wearer in the usual manner.

All it is necessary to do in attaching my 60 garter is to pass the band 1 around the leg, pass the knob portion 17 through the loop 5 so as to pass longitudinally of the loop 6 into the recess 8 of the cross piece 7, pressure is thereby exerted against the cross 65 piece which compresses the spring 11 towards the closed end of the loop 6 and thereby provides resilient tension for the garter around the leg of the wearer so that it will give more or less according to the 70 wearer's movements and always exert a firm yet comfortable hold around the leg.

It may be also pointed out that as the plate 13 is secured to the pad 12 by means of stitching passing through the slots 15 75 at each side of the plate, and the headed member being located centrally of the plate that any play of the loop 6 of the cast off 4 takes place longitudinally of the plate 80 from such headed member and between the stitching passing through the slots 15. It will therefore be seen that there is no danger of the stitching being cut by a continuous rubbing action of any portion of the garter thereagainst.

What I claim as my invention is:

1. In a garter, the combination with a non-elastic divided band, a cast off secured to one end of the band and provided with a longitudinally extending metallic loop 90 opened at one end and closed at the opposite end, a cross piece slidable upon the arms of the loop, a spiral spring coiled around the arms of the loop and the closed end thereof, against the ends of which the cross piece 95 bears, a headed stem carried by the opposite end of the band and adapted to enter the open end of the loop to bear against the cross piece to compress the spring towards the closed end of the loop, and means for 100 detachably connecting the band to the sock of the wearer.

2. A garter comprising a band of non-elastic material, a pad secured to one end of the band provided with means for detachably connecting the band to the stocking of the wearer, a plate provided with longitudinally extending side slots, stitch-

ing adapted to pass through the slots to connect the same to the pad, a headed stem carried by the plate in alignment with the longitudinal centre thereof, a cast off carried by the opposite end of the band, a longitudinally extending loop forming part of the cast off and adapted to contact with the

plate between the aforesaid slots, and resilient means carried by the loop against which the headed stem bears to compress ¹⁰ such resilient means towards the closed end of the loop.

ROBERT HOWARD BIGGS.
